UNITED STATES PATENT OFFICE

165,244

FOUNDATION VENTILATOR

Albert Rendessy, Glendale, Calif.

Application August 5, 1950, Serial No. 11,617

Term of patent 3½ years

(Cl. D62—4)

To all whom it may concern:

Be it known that I, Albert Rendessy, a citizen of the United States of America, residing at Glendale, in the county of Los Angeles and State of California, have invented a new, original, and ornamental Design for a Foundation Ventilator, of which the following is a specification, reference being had to the accompanying drawings, forming a part thereof.

In the drawings,

Figure 1 is a front perspective view of a foundation ventilator embodying my new design; and

Figure 2 is a section taken on line 2—2 of Figure 1.

I claim:

The ornamental design for a foundation ventilator, as shown.

ALBERT RENDESSY.
